CAR-DOOR.

1,067,547.

Specification of Letters Patent. Patented July 15, 1913.

Application filed March 31, 1910. Serial No. 552,717.

To all whom it may concern:

Be it known that I, EDWARD POSSON, a citizen of the United States, residing at Chicago, in the county of Cook and State of Illinois, have invented certain new and useful Improvements in Car-Doors, of which the following is a specification.

The principal object of my invention is to provide a new and improved door for railway freight cars.

Another object of my invention is to provide a door for railway freight cars that shall be adapted to hold grain in the car.

Another object of my invention is to provide a sheet metal outside door for freight cars.

A further object of my invention is to provide a door that shall have some or all of the following characteristics; convenient to manipulate, secure when closed, simple and inexpensive in construction, not liable to get out of order.

My invention is defined in the appended claims. In the accompanying drawings I have shown one specific embodiment thereof which I now proceed to describe in this specification.

Figure 1 is a front elevation of the entire door. Fig. 1^a is a vertical section of the entire door, taken on the line 2—2 of Fig. 1. Fig. 2 is a section of the upper part of the door taken on the line 2, 2 of Fig. 1. Fig. 3 is a section on the same line of the intermediate part of the door. Fig. 4 is a section on the same line of the lower part of the door. Fig. 5 is a horizontal section on the line 5, 5 of Fig. 1. Fig. 6 is a horizontal section on the line 6, 6 of Fig. 1. Fig. 7 is a horizontal detail section on the line 7, 7 of Fig. 1. Figs. 8 and 9 are vertical sections taken on the line 8, 9 of Fig. 1. Fig. 10 is a detail elevation of one of the auxiliary doors. Fig. 11 is a top edge view of the same. Fig. 12 is an end view of the same, and Fig. 13 is a perspective view of a guide.

The side wall of the freight car has the sill 15, the side posts 16 and the top frame member 17.

The door disclosed in the drawings is an outside door comprising two main sections, an upper section 18 and a lower section 19.

Attached to the top frame member 17 above the door opening is the Z-bar 20, having one flange lying against the car wall and the other flange hanging downward. This

Z-bar affords a track and guide on which the top section 18 is hung. The top door section 18 is of sheet metal with two parts 29 at the upper corners struck out as shown in the drawings. To these struck out portions 29 hangers 21 are attached by means of rivets and they carry rollers 22 which engage the track 20.

The upper door section 18 is shown in horizontal section in Fig. 6. At the right a vertical strip or cleat 23, with out-turned edge, is secured to the door post 16 by means of bolts 24. The right-hand edge of the door section 18 is doubled over, as indicated by the reference numeral 25, and adapted to slip tightly under the lip 23. At the left-hand side, the door section 18 has riveted to its edge a hook-shaped strip 27 which, when the door is closed, engages the strip 26 fastened to the door post 16 by means of bolts 28. Thus it will be seen that when the door section 18 is closed by moving it to the right, the lip 23 engages and holds its right-hand edge 25 and the strip 26 engages and holds the hooked left-hand edge 27.

The lower door section 19 opens to the right, this direction being the opposite of that for the upper door section 18. The various coacting elements 23', 24', 25', 26' and 27' correspond, respectively, to the parts designated with the corresponding numerals in connection with the upper door section 18.

The lower edge of the upper door section is offset to form a stiffening rib 31 shown in Fig. 2. It is further strengthened by a metal bar 30, riveted adjacent to the offset 31 by means of the rivets 32. The extreme edge of the door section 18 is doubled, as indicated by the reference numeral 33.

Attached to the side posts 16 are guide blocks 34, each having a T-head 35, and secured in place by means of bolts 36. The T-heads 35 enter the pocket 31 on the lower edge of the upper door section 18 and hook under the metal bar 30. Thus the T-head blocks 34 form retaining guides for the lower edge of the upper door section 18. The upper edge 37 of the lower door section 19 is doubled over and projects under the T-heads 35 of the guide blocks 34. Thus these T-head guide blocks form retaining guides for the upper edge of the lower door section 19.

The lower door section 19 is strengthened by having three transverse ribs 41 struck

out from its surface, and an additional transverse rib 42 below these is similarly struck out. Across the lower part of this door section 19 transverse Z-bars 43 and 44 are riveted, with their free flanges opposed to one another to form retaining guides for the auxiliary sliding doors 45. Each door 45 consists of a sheet of metal with its edge 46 turned outwardly to give strength and 10 with an angle bar 47 riveted along the edge toward the center of the main door. Each auxiliary door 45 normally closes an opening in the main door section 19, these openings having in-turned edges 48. Furthermore, the edges adjacent to the center of the door section 19 are doubled back, as indicated by 49 in Fig. 7, so as to engage the angle bar 47 when the door 45 is closed. Vertical Z-bars 50 extending between the 15 Z-bar guides 43 and 44 form abutments for the auxiliary doors 45 when closed. The outer flanges of the Z-bar guides 43 and 44 are deflected inwardly at 51 (see Figs. 7 and 8), so as to hold the auxiliary doors 45 tight 20 against the auxiliary door openings when they are in closed position.

Riveted at the center of the strengthening rib 42 is the bracket 52 which carries a central pivotal bolt or rivet 53 on which the lever 54 is fulcrumed. At the lower end of this lever 54 is a handle 55 and a locking bar 56 is pivotally attached to the other end by means of the rivet 57. This locking bar 56 is adapted to reciprocate in the guide 30 clips 58, which are made wide enough to allow for necessary lateral movement of the bar 56. On the upper edge of the door section 19 is a clip 59, and on the lower edge of the door section 18 is an opposed clip 60, 35 these two clips registering when the doors are closed and being both engaged by the bar 56 when it locks them in closed position.

Pivottally attached to the lever 54 is the 45 end of the link 61, the other end 62 thereof being offset and connected by the pivot pin 63 to the end of the crank arm 65 on the rotary shaft 64. This shaft 64 is rotatably mounted in brackets 66 and its ends 50 are offset as indicated by the reference numerals 67. When in locked position, these offsets 67 lie directly adjacent to the ends of the auxiliary doors 45, thus locking the latter in closed positions.

55 A heavy angle bar having one flange much wider than the other is provided for a door sill, the flange 70 (Fig. 4) lying on the wooden sill 15 and the narrow flange 71 projecting upwardly to afford a track for the 60 rollers 74. These rollers 74 are supported between brackets 73 and the reinforcing plate 72 which extends across the lower edge of the lower door section 19. The lower edge of the main sheet metal plate 19 is off- 65 set as indicated by the reference numeral 68

and its extreme edge is doubled as indicated by 69. The lower ends of the brackets 73 are hooked under, as indicated by 75, so as to keep the rollers 74 on the track 71. The angle bar 70-71 not only extends across the lower edge of the door opening, as shown in Fig. 4, but also extends off to the right, so as to afford a track for the rollers 74 when the door section 19 is opened to the right. This portion of the bar 70-71 at the right 75 of the door opening has the flange 70 bent down, as indicated by 70', and bolted to the side wall of the car.

The hasp 77 on the staple 76 is adapted to lap over the lever 54 and have its free end secured in place by the bolt 78 engaging the staple 79.

80 is a pivoted stop which hangs by gravity in a position to hold the bolt 78 in its place.

It will be observed that when the parts have the relation shown in the drawings, the upper door section is prevented from moving to the right because the edge 25 is pushed tightly under the lip 23. In a similar manner the lower door section 19 is prevented from moving to the left. Moreover, the doors are locked together by means of the bar 56 engaging the loops 59 and 60, and thus both door sections 18 and 19 are 90 locked against movement in either direction. At the same time that the door sections are locked together, as described, the auxiliary doors 45 are locked in closed position by the offsets 67. Of course the locking 100 action that has just been described can be made secure against interference by sealing the hasp 77 to the staple 79 so as to prevent any movement of the lever 54. When it is desired to open the doors the hasp 77 105 must be released, and then by swinging the lever 54 to one side the auxiliary doors 45 will be released and at the same time the locking bar 56 will be withdrawn from the clip 60. Then, if desired, the upper door section 18 can be moved aside to look into the car without disturbing the lower door section 19. If there is grain in the car the auxiliary doors 45 can be opened so as to permit it to run out and relieve the pressure 110 against the door section 19 preparatory to opening the latter. The inverse operation of closing and locking the doors will be readily apparent. It will be observed that the top and bottom edges of the door sections are restrained at all times from swinging out away from the car wall. The T-heads 35 restrain the bottom edge of the upper section 18 and the top edge of the lower section 19. The lateral edges of the door sections securely engage the coacting strips or cleats fastened to the side posts, so that when the doors are closed, not only 115 are they held strongly against pressure from within, but there is a tight fit that pre-

vents the escape of grain from within the car.

It will be seen from the foregoing specification that I have invented a door especially adapted to railway freight cars, which serves as an ordinary outside door, but is also adapted to retain grain in the car, thus at the same time fulfilling the additional function of a grain door. It will be seen that I have provided secure means for holding this door against the pressure of the grain from within and that I have avoided possible cracks or gaps where grain might escape; also that I have provided secure means for locking the door sections in closed position.

I claim:

1. In a device of the class described, a door comprising upper and lower horizontally movable sections, the lower edge of the upper section being struck out and lapping past the upper edge of the lower section, a downwardly projecting plate attached along the lower edge of the upper section above the said struck out portion, and T-heads attached to the side post of the door openings, said T-heads lying within the said struck out portion and engaging the said downwardly projecting plate and the top edge of lower door section.

2. In a device of the class described, a door, two auxiliary door openings therethrough, sliding covers for the same, and means to simultaneously lock the door and the sliding covers.

3. In a device of the class described, a door having auxiliary door openings therethrough, sliding covers for the same, a main locking bar on the door, displaceable stops to control the sliding covers, and mechanism to simultaneously operate said locking bar and stops.

4. In a device of the class described, a

sliding door, a metal door sill consisting of an angle iron having one flange directed up 45 to act as a track, part of the other flange acting as a door sill and the remainder of said other flange being turned down and attached to the side wall of the car, and rollers carried by the lower edge of the door 50 engaging said upwardly directed flange.

5. In a device of the class described, a door comprising upper and lower horizontally movable sections, and T-heads attached to the side posts of the door opening, the 55 lower edge of the upper section and the upper edge of the lower section having portions extending under said T-heads.

6. In a device of the class described, a door comprising upper and lower horizontally movable sections, the upper section being supported at the top thereof and the lower section at the bottom thereof, and guides engaging the meeting edges of the two sections, said guides comprising T- 65 heads on the two side posts of the door, said T-heads overhanging portions of said meeting edges.

7. In a device of the class described a sliding outer door, a metal door sill consisting of an angle iron substantially twice the width of the door and extending across the lower part of the door opening and to one side thereof, one flange of said angle iron being directed up along the whole 70 length thereof and the other flange directed horizontally in across the lower part of the door opening and being turned down and attached to the side wall the rest of the way.

In testimony whereof, I have subscribed my name.

EDWARD POSSON.
